UNITED STATES PATENT OFFICE

WILLIAM SCOTT, OF MEDFORD, MASSACHUSETTS, ASSIGNOR TO THE DALTON-INGERSOLL COMPANY, OF BOSTON, MASSACHUSETTS.

DESIGN FOR A LAVATORY-BOWL.

SPECIFICATION forming part of Design No. 27,064, dated May 18, 1897.

Application filed September 14, 1895. Serial No. 562,583. Term of patent 14 years.

To all whom it may concern:

Be it known that I, WILLIAM SCOTT, of Medford, county of Middlesex, State of Massachusetts, have invented a new and original 5 Design for a Lavatory-Bowl, of which the following description, in connection with the accompanying drawings, is a specification, like letters on the drawings representing like parts.

10 Figure 1 is a perspective view of the bowl embodying the design, looking from a position somewhat above and to the right of the said bowl; and Fig. 2 is a top plan view of the same, partly in section.

15 The design forming the subject of the present invention is embodied in a lavatory-bowl having a rounded concavo-convex lower portion *a* and a horizontal portion *b*, extending laterally from a part only of the upper edge 20 thereof and presenting a substantially flat surface continuous with the said upper edge and extending partly around the same. Surrounding the extreme outer periphery of the complete bowl—that is, the portion *a* and the 25 horizontal portion *b*—is a convex marginal portion *c*, rising above the edge of the con-

cavo-convex portion *a* and the surface of the horizontal portion *b*. The said convex marginal portion is continuous with and rises directly from the upper portion of the concavo-convex portion *a* at the front part of the bowl, as shown in Fig. 2, but flares laterally outward therefrom at the beginning of the horizontal portion *b* and extends along and rises above the edge thereof around the remainder 30 of the periphery of the bowl. 35

As a secondary non-essential feature of the design the upper surface of the horizontal portion *b* may be provided with intaglio designs *b*², extending to the junction of said 40 horizontal portion with the inner surface of the concavo-convex portion *a*.

I claim—

The design for a lavatory-bowl substantially as herein shown and described. 45

In testimony whereof I have signed my name to this specification in the presence of two subscribing witnesses.

WILLIAM SCOTT.

Witnesses:

M. E. HILL,
H. J. LIVERMORE.
